CARBON CLAMP

Carl E. Graham, Canton, Ohio

Application July 29, 1946, Serial No. 686,933

6 Claims. (Cl. 176—119)

1

The invention relates to carbon clamps and more particularly to a clamp especially designed for holding the carbon in the lamp house for the usual type of motion picture projectors, and the present invention is a continuation in part of my co-pending application Serial No. 587,132, filed April 7, 1945, abandoned August 21, 1946.

In the type of lamp house which is commonly used in connection with motion picture projectors, due to the construction of the lamp house and projector, the feed screw which feeds the positive carbon toward the arc is limited to ten inches in length, and since the carbons which are provided for this purpose are fourteen inches in length, it is not possible to clamp a new full length carbon at its extreme end when the same is first placed in the lamp house.

This requires clamping the carbon about four inches from the end until a sufficient amount of the carbon has been burned away to permit it to be clamped at its end. It frequently happens that this initial clamping of the carbon at a point spaced from its end cracks or fractures the carbon at this point and since these carbons are covered with a copper coating the cracks or fractures are not visible from the exterior.

However, as the carbon is used this cracked or fractured portion reaches the arc and produces a very unsatisfactory condition causing what is commonly referred to in the industry as a blue light, frequently resulting in such a poor lighting effect that the damaged carbon must be immediately removed and replaced and this may happen while a film is being run through the projector causing considerable annoyance and difficulty.

In this common type of lamp house the post which is operatively connected to the feed screw and carries the carbon clamp is inclined forwardly at substantially a 45° angle to the vertical, and a relatively short head for the carbon clamp is pivotally connected to the upper end of this post, the main lead wire being connected to the rear end of the carbon clamp.

This requires that the forward end of the head be provided with a weight to counter balance the weight of the lead wire so as to hold the forward end portion of the positive carbon down in the usual V-shape guide ordinarily provided for that purpose.

My invention contemplates an improvement in such lamp houses which comprises a vertical post mounted upon the positive feed screw and an elongated head which is pivotally mounted at its rear end upon the upper end of said vertical

2

post and carries the carbon clamp, whereby the forwardly extending elongated head is of sufficient weight to counter-balance the lead wire and hold the carbon down in the V-shape guide.

5 The object of the present invention is to provide a novel carbon clamp for such use which will overcome the objections and difficulties above referred to.

Another object is to provide a carbon clamp 10 which will clamp the end of a new carbon when it is first installed in the lamp house and in which an adjustment is provided in the clamp itself to compensate for the difference in length between the new carbon and the usual feed screw 15 in the lamp house.

A further object is to provide a carbon clamping device of this character which may be attached to the positive post of the lamp housing replacing the conventional carbon clamp.

20 A still further object is the provision of a carbon clamp comprising an elongated head for attachment to the positive post and provided with a guideway and a carbon clamping member adjustably mounted in the guideway of said head.

Another object of the invention is to provide a carbon clamp including an elongated head having a depending ear near one end and a counterweight formed upon the adjacent end 30 of the head.

It is still another object to provide a carbon clamp in a lamp house having a feed screw of considerably less length than the carbon, said device comprising an elongated head of a length corresponding to the difference in length between the feed screw and the carbon, and a carbon clamp adjustably mounted upon said elongated head.

40 A further object of the invention is to provide a device of the character referred to including a vertical post operatively mounted upon said screw, an elongated head pivotally connected at its rear end to the vertical post and a carbon clamp adjustably mounted upon the elongated head.

The above objects together with others which will be apparent from the drawing and following description, or which may be later referred to, may be attained by constructing the improved carbon clamp in the manner illustrated in the accompanying drawing, in which:

Figure 1 is a fragmentary longitudinal sectional view of a portion of the interior of a lamp house showing the positive feed screw and positive post, with the improved carbon clamp

mounted thereon in the position to which it is adjusted when a new carbon is inserted;

Fig. 2 a fragmentary elevation of the improved carbon clamp and the upper portion of the positive post upon which it is mounted showing the carbon clamping device in the position to which it is later adjusted after the carbon has been partly burned away by use;

Fig. 3 an enlarged transverse section taken as on the line 3—3, Fig. 2;

Fig. 4 a fragmentary bottom plan view of a portion of the head of the improved carbon clamp showing the terminal clamp for the main lead wire;

Fig. 5 a detached perspective view of the head;

Fig. 6 a detached perspective view of the adjustable clamp;

Fig. 7 a fragmentary, longitudinal sectional view of a portion of the interior of a lamp house showing the positive feed screw with a vertical positive post mounted thereon and the elongated head pivotally connected at its rear end to the vertical post and the carbon clamp upon the elongated head adjusted to the position for receiving a new full length carbon;

Fig. 8 an enlarged detached elevation of the upper portion of the vertical positive post and the elongated head mounted thereon showing the carbon clamp in the position to which it is adjusted after the carbon has been partially burned away by use; and

Fig. 9 a detached perspective view of the elongated head shown in Figs. 7 and 8.

Referring first to Fig. 1, in which is shown a portion of the interior of a conventional lamp house such as used in motion picture projectors, the reflector is indicated generally at 10 and a portion of the negative carbon is shown at 11. As in usual practice, this negative carbon is designed to be fed through the central opening 12 in the reflector toward the positive carbon.

The usual positive feed screw is indicated at 13 and provided with the gear 14 at one end by means of which it may be operatively connected to a motor for rotating the feed screw to feed the positive carbon toward the negative carbon at a uniform rate of speed as in ordinary practice.

The usual positive saddle 15 is mounted upon the feed screw 13 and provided with the handle lever 16 by means of which the saddle may be engaged with or disengaged from the screw. The usual positive post 17 is mounted upon the saddle 15 and provided at its upper end with the spaced ears 18 to which the ordinary carbon clamp is adapted to be connected.

This much of the mechanism is of the same construction as provided in a type of lamp house widely used in connection with motion picture projectors. Owing to the limitations of space within such lamp houses the positive feed screw 13 can not be more than about ten inches long.

However the carbons provided for such lamp houses are fourteen inches in length and this requires that when a new carbon is inserted into the lamp the carbon can not be clamped at its end but must be clamped not less than four inches from the end.

This clamping of the carbon at a distance from its end frequently results in injury to the carbon at this point by cracking or fracturing the same. Owing to the fact that these carbons have a copper coating upon the exterior this damage to the interior of the carbon is not usually discovered until the carbon has been burned down

in length to a point where it may be adjusted in the clamp so that only the end of the carbon is clamped and the damaged portion has been fed into the arc. This results in what is known as a blue light, spoiling the showing of the picture and causing a very unsatisfactory condition.

The present invention contemplates replacing the ordinary carbon clamp upon the positive post as 10 by an adjustable clamp which includes generally the elongated head 19 and the adjustable carbon clamp 20. Both of these members are formed of suitable conductor metal, the head 19 being preferably made of cast iron or similar metal and the clamp 20 of steel or the like. The head 19 is provided with a depending ear 21 adapted to be received between the ears 18 of the positive post and pivotally attached thereto as by the usual screw or bolt 22.

The main lead wire 23 may be connected to the head 19 by means of a terminal comprising the lug 24 formed upon the under side of the head 19 and provided with the serrated half round recess 25 to receive the wire, a correspondingly shaped cap 26 being connected to the lug as by the screws 27 for clamping the lead wire therebetween.

The head 19 is provided with a longitudinal guideway comprising the lower flange 28 and upper flange 29 forming a channel in which the clamping member 20 is slidably mounted. For the purpose of permitting longitudinal adjustment of the clamping member 20 within this guideway and for clamping it at any adjusted position, an elongated longitudinal slot 30 is formed in the head 19 and a clamping screw 31 is located through said slot and through a transverse opening 32 in the clamping member 20, a thumb nut 33 being provided upon the screw 31 for holding the clamp in adjusted position upon the head.

In the event that it is necessary to locate the depending ear 21 adjacent to the inner end of the head 19, as shown in the drawing, a depending counterweight 34 may be formed upon this end of the head to counterbalance the outer end portion of the head located beyond the pivot of the screw 22, so as to hold the positive carbon, indicated at 35, in horizontal position so that the free end portion thereof will feed through the usual V-shape guide notch 36 in the post 37 ordinarily provided for that purpose.

The inner end of the clamp 20 is provided with a longitudinal socket 38 of a diameter to receive the end of the carbon 35 and the clamp is slit longitudinally, through said socket as at 39, the clamping screw 40 being provided for clamping the end of the carbon within the end of the socket.

The inner end of the clamp is formed V-shaped on its under side as at 41 so that it may be guided through the V-shaped guide notch 36 whereby the entire carbon may be burned with the exception of the small end thereof clamped with the socket 38.

With this construction it will be obvious that when a new positive carbon is installed in the lamp the end thereof is clamped in the socket 38 of the clamping member 20 and remains therein until the entire carbon has been consumed. When the new carbon is first installed, the clamp 20 is adjusted to the outer or right hand end of the head 19 as shown in Fig. 1. After several inches of the carbon has been burned away the clamp 20 may be moved to the inner or left hand

end of the head as shown in Fig. 2 and clamped in this position by means of the nut 33.

To carry out this adjustment it will of course be understood that the saddle 15 may be disengaged from the screw 13 by means of the handle and moved to the necessary position upon the feed screw 13 and again engaged therewith.

Referring now to the construction shown in Figs. 7, 8 and 9, the reflector is indicated at 10' and a portion of the negative carbon 11' is shown located through the central opening 12' therein. The positive feed screw is indicated at 13' and provided with the usual gear 14' at its rear end for operatively connecting the screw to a motor as in usual practice in order to feed the positive carbon toward the negative carbon at a uniform rate of speed.

The positive saddle 15' may be of conventional construction and is operatively mounted upon the feed screw and provided with the usual handle lever 16' by means of which the saddle may be operatively engaged with or disengaged from the said screw.

Instead of providing the usual forwardly inclined positive post as shown in Fig. 1, the positive post 17' in this form of the invention is vertical and is mounted upon the saddle 15' in usual manner and provided at its upper end with the spaced ears 18'.

As above pointed out with reference to Fig. 1, owing to the length of space within the usual type of lamp house the positive feed screw 13' is limited in length to about ten inches while the carbons which are furnished for use in such lamp houses are made in fourteen inch lengths.

The elongated head 19' which is designed for use with the vertical positive post 17' is provided at its rear end with the depending ear 21' adapted to be received between the spaced ears 18' of the positive post and pivotally attached thereto as by the usual screw or bolt 22'.

A rearwardly extending lug 24' is formed upon the depending ear 21' and the clamping cap 26' is connected thereto as by the screws 27' for clamping the lead wire 23' thereto.

The carbon clamp 20' is mounted upon the elongated head 19', between the lower flange 28' and the upper flange 29' thereon which form a guide channel in which the carbon clamp is slidably mounted. The elongated slot 30' is formed in the head 19' between the flanges 28' and 29' and a clamping screw 31' is located through the carbon clamp 20' and through said slot and provided with a thumb nut 33' for holding the carbon clamp in adjusted position upon the head.

The carbon clamp 20' may be identically the same as carbon clamp 20 shown in Figs. 1 to 6 inclusive and the end of the positive carbon 35' is clamped within the socket 38' of the carbon clamp in the manner above described.

The elongated head 19' extending forwardly from the pivot point 21' upon the positive post is of sufficient weight to counterbalance the weight of the lead wire 23' so as to hold the positive carbon clamp 35' in horizontal position so that the free end portion thereof will feed through the usual V-shape guide notch 36' in the post 37' ordinarily provided for that purpose.

In this form of the invention as in the form shown in Figs. 1 to 6 and above described, when a new positive carbon is installed the end thereof is clamped in the socket 38' of the carbon clamp 20' and remains there until the entire carbon is consumed. When the new carbon is first inserted the clamp 20' is adjusted to the rear or right

hand end of the elongated head 19' as shown in Fig. 7.

After several inches of the carbon has been burned away the carbon clamp 20' may be moved to the left or forward end of the head as shown in Fig. 8 and clamped in this position by means of the nut 33' in the manner above described with reference to Figs. 1 to 6 inclusive.

From the above it will be obvious that the improved carbon clamp eliminates the necessity of clamping the carbon at any point along its usable length, thus avoiding any cracking or fracturing of any portion of the carbon which will later be used. It also eliminates the necessity of handling hot carbons and carbon savers such as are generally used.

Furthermore it should be noted that the improved carbon clamp does not present a surface facing the lamp greater than the ordinary clamp now in use, so that the efficiency of the lamp is not in any way impaired.

I claim:

1. A carbon holder for an arc lamp having a movable post therein and feed means for moving the post, said carbon holder comprising an elongated head, means for detachably connecting said head to the post, a clamping member adjustably mounted upon the head and having a socket for receiving one end of the carbon, and means for clamping the clamping member in adjusted position upon the head at any point throughout the length of the head.

2. A carbon holder for an arc lamp having a movable post therein and feed means for moving the post, said carbon holder comprising an elongated head extending a substantial distance back of the post and having a depending ear, means for detachably connecting said depending ear to the post, there being a longitudinal guideway and a longitudinal slot in the head, a clamping member adjustably mounted in said guideway and having a socket for receiving one end of a carbon, and a clamping screw carried by the clamping member and located through said slot for clamping the clamping member in adjusted position at any point in the guideway.

3. A carbon holder for an arc lamp having a movable post therein and feed means for moving the post, said carbon holder comprising an elongated head, means connecting the rear end of said elongated head to the post, a clamping member adjustably mounted upon the head and having a socket at its forward end for receiving one end of the carbon, and means for clamping the clamping member in adjusted position upon the head at any point throughout the length of the head.

4. A carbon holder for an arc lamp having a movable post therein and feed means for moving the post, said carbon holder comprising an elongated head, means pivotally connecting the rear end of said elongated head to the post, a clamping member adjustably mounted upon the head and having a socket at its forward end for receiving one end of the carbon, and means for clamping the clamping member in adjusted position upon the head at any point throughout the length of the head.

5. A carbon holder for an arc lamp having a movable post therein and feed means for moving the post, said carbon holder comprising an elongated head, means for pivotally connecting said head to the post, a clamping member adjustably mounted upon the head and having a socket for receiving one end of the carbon, and means for

clamping the clamping member in adjusted position upon the head at any point throughout the length of the head.

6. A carbon holder for an arc lamp having a movable post therein and feed means for moving the post, said carbon holder comprising an elongated head, means connecting the rear end of the head to the post, there being a longitudinal guideway and a longitudinal slot in the head, a clamping member adjustably mounted in said guideway and having a socket at its forward end for receiving one end of the carbon, and a clamping screw carried by the clamping member and located through said slot for clamping the clamp-

ing member in adjusted position at any point in the guideway.
